COMBINED INK MARKING AND PERFORATING MACHINE

Arthur W. Altwater, University City, Mo.

Application March 1, 1937, Serial No. 128,314

4 Claims. (Cl. 101—316)

The present invention relates to shoe machines and more particularly to a machine for performing a combined ink-marking and perforating operation.

For purposes of disclosure the various features of the present invention are illustrated and described as embodied in the model R machine manufactured by Western Supplies Company, under my prior patents, Nos. 1,834,919 and 1,938,678, 10 which machine has a wide use in the manufacture of shoes to perform many different operations.

Heretofore Western Supplies Company performed the combined ink-marking and perforating operation upon the well-known Western cutting machine.

The principal objects of the present invention are to produce a simple, inexpensive and efficient combined ink-marking and perforating machine, particularly in the form of an attachment to the 20 model R machine, to simplify and improve the inking means by which the marking die is provided with ink, and to simplify and improve the die holder, particularly, with respect to the retaining of the chips cut out of the work by the die and the discharge of the retained chips, and 25 with respect to the securing of the die holder for ready removal in the machine.

To the accomplishment of these objects, and such others as may appear hereinafter, the various features of the present invention reside in certain devices, combinations and arrangements of parts hereinafter described and then set forth broadly and in detail in the appended claims which possess advantages readily apparent to those skilled in the art.

The various features of the present invention will be readily understood from an inspection of the accompanying drawings illustrating the best form of the invention at present known to the 40 inventor, in which

Figure 1 is a view in front elevation of the combined ink-marking and perforating machine;

Fig. 2 is a view in right side elevation;

Fig. 3 is a detail view in perspective showing 45 particularly how the work is gauged when paper is used on the metallic cutting bed;

Fig. 4 is a detail view partly in section in underside plan of the die, the die holder plate, the plunger plate and the means for securing these plates together;

Fig. 5 is a detail view in sectional elevation on the line 5—5, Fig. 4;

Fig. 6 is a detail view in sectional elevation on the line 6—6, Fig. 4;

Fig. 7 is a detail view in plan of a modified form of the ink pad operating mechanism, the cutting bed being shown without the paper illustrated in Figs. 1, 2 and 3;

Fig. 8 is a detail view in front elevation of the 60 parts illustrated in Fig. 7, and

Fig. 9 is a detail view in left-side sectional elevation showing the stop for limiting the downward movement of the die under the influence of the left-hand treadle.

In the embodiment of the invention illustrated in the drawings, the frame of the machine is shown as including a base 9 (Fig. 1), which is rigidly secured to a permanent horizontal support 10 mounted on legs 11. Integrally formed with the base is an irregularly shaped boss 12 constituting the work supporting bed. An overhanging arm is integrally cast with the base 9 and includes the standard 13 (Fig. 2), and the overhanging head 14. In the upper parts of the standard and head is an elongated journal for the 15 drive shaft 15. The shaft 15 is operatively connected for intermittent rotation with the pulley 16 which is driven constantly from some suitable source of power.

Between the pulley 16 and the shaft 15 is a 20 clutch mechanism 17 controlled from a foot treadle 18 through a link 19. The clutch construction is generally similar to that employed in the machine disclosed in my prior Patent No. 1,807,952, dated June 2, 1931, which is referred to and described in my prior Patent No. 1,834,919, 25 at page 2, lines 32 et seq. Since the construction and operation may be readily understood by reference to my prior patents, it is unnecessary to repeat the description of the construction and mode of operation of the clutch mechanism except to direct attention to the fact that the shaft 15 is operated intermittently.

The shaft 15 carries at its front end an eccentric 30 (Fig. 1), which rotates within a strap 21 having a downwardly extending arm 22. The arm 22 extends between a pair of spaced arms 23 (Fig. 2), forming upward extensions of a sliding plunger 24. A pin 25 provides a pivot connection between the arm 22 and the arms 23. The plunger 24 is mounted in a guideway formed 35 on the front face of the head 14. A plate 26 having a rectangular cut-out portion is attached to the walls of the guideway by screws 27. A die carrier in the form of a rectangular sliding block 28 is mounted in the lower part of the guideway 40 in axial alignment with the plunger 24.

The connection between the plunger and the die carrier is generally the same in construction and mode of operation as the connection shown 45 in my prior Patent No. 1,938,678, so that it is unnecessary to repeat that description.

The die carrier 28 is provided with a lateral pin 29, (Fig. 9), which slides in a curved slot 30 formed in the left-hand side of the head 24, 50 viewing Fig. 1. This pin 29 is embraced by the forked end of a bell-crank lever 30 pivoted at 31 on the standard 13 and is operated from the left-hand foot treadle 32, (Fig. 1), through a link 33.

When the forward end of the lever 30 is moved downwardly by the link 32, the die carrier is moved downwardly in opposition to the spring 34, (Fig. 9), which downward movement is limited by a stop pin 35, (Fig. 9), on the standard 13.

As explained in my prior Patent No. 1,834,919, the preliminary downward movement of the die carrier provides a safety mechanism preventing accident to the operative's fingers. Heretofore the cutting edge of the die was moved, during the preliminary downward movement, into engagement with the work prior to the throwing in of the clutch to drive the edge of the die through the work. In the illustrated embodiment of the present invention the downward movement of the die carrier 28 is limited by the stop pin 35 to space the cutting edge of the die slightly above the work, the space, however, being too small to receive any portion of the operative's finger.

The bottom face of the die carrier 28 is flat, (Fig. 5), to receive flatwise one face of a plate 36 provided with a pair of mutilated pins 37 which enter vertical sockets 38 formed in the die carrier 28. The plate 36 is secured to the die carrier 28 by frusto-conical surfaces 39, (Figs. 4 and 5), which engage the mutilated portions of the pins 37, respectively. The surfaces 39 are formed on elongated pins 40 mounted to slide in horizontal openings 41 formed in the die carrier 28. Each surface 39 is held in engagement with the mutilated portion of one of the pins 37 by a spring 42 coiled about a reduced portion of the pin 40 and interposed between the pin 40 and a web 43 of the die carrier 28, a screw 44 carried by the end of the pin 40 acting by engagement with the web 43 as a stop for limiting the movement of the pin under the influence of the spring. Both pins 40 are connected to a common handle 45 for operating them to release the pins 37, there being a stop 46 on the die carrier 28 for limiting the inward movement of the handle. The pins 40, adjacent the surfaces 39, are provided with a cylindrical portion 47 of reduced diameter to permit the pins 37 to be readily withdrawn from the sockets 38 when the handle 45 is pushed inwardly.

The plate 36 is riveted to the reduced upper ends of four posts 48 the lower reduced ends of which pass through a die block 49, a die rest plate 50, and a die holding plate 51, the lower ends of the posts 48 being riveted to the plate 51. The dies held by the plate 51 comprise a cut-out die 52 and a plurality of perforating tubes 53. The ink-marking die is provided with two continuous marking edges 54 and 55 formed upon a stripper plate 56 which is supported upon the lower ends of four posts 57 loosely mounted in the plates 50 and 51. Each of the posts 57 is held from dropping out by a sleeve 58 to which the post is pinned, the sleeve 58 being mounted in a recess 59, formed in the block 49. The sleeve 58 is held normally in engagement with the plate 50 by a spring 60 coiled about the post 57 and interposed between the stripper plate 56 and the bottom of a recess 61 formed in the plate 50.

The space between the plate 36 and the block 49 is enclosed by a rectangular sheet metal wall 62 the bottom of which is secured to the four edges of the block 49 and the top of which is secured to the two narrow edges of the plate 36. The wall 62 forms a chamber 63 for retaining the chips or pills formed by the cut-out die 52 and the perforating tabs which work up from the dies into the chamber 63 through inlet passages 64 and 65, respectively. If the stripper plate

post 57 were mounted in the usual manner chips or pills in the chamber 63 would prevent the stripper plate 56 from returning to its original position after each ink-marking and perforating operation. By securing the posts 57 to the sleeves 58 and by mounting the sleeves 58 in the counterbored recesses 59 all dangers of the chips or pills interfering with the proper operation of the stripper plate is obviated.

The plate 36 is provided with an outlet 66 which is normally closed by the bottom of the die carrier 28. To clear the chamber 63 of chips the handle 46 is pressed inwardly to release the pins 37 thus permitting the plate 36 and the die structure assembled therewith to be withdrawn from the die carrier 28. After the plate 36 has been separated from the bottom of the die carrier 28, the die structure may be turned into an upside down position whereupon the chips or pills in the chamber 63 may be shaken out through the outlet 66.

In some cases, it may be desirable to support the work upon a flat plate 67, (Fig. 7), constituting the cutting bed, supported removably upon the flat upper surface of the work supporting bed 12. To this end the bed 12 is provided with four upstanding pins 68 which are received by four openings 69 formed in the plate 67. The work may be gauged by an abutment gauge plate 70 removably mounted upon the plate 67. To this end the plate 70 is provided with two holes 71 which receive pins 72 projecting from the bed 12 through suitable openings formed in the work supporting plate 67.

In other cases it may be desirable to support the work upon a sheet of paper 73 which is fed over the work supporting plate 67 between the pins 68. When the paper is employed as the normal cutting bed a gauge plate 74, (Fig. 3), is used. This plate 74 is provided with openings 75 which receive pins 72 projecting upwardly from the upper surface of the plate 67 outside the path of the paper 73.

In the illustrated embodiment of the invention the gauges 67 and 74 are shaped to engage the throat 77 of a vamp 78, but it will be understood that these gauges may be shaped to engage selected edges of any shoe upper part upon which it is desired to perform the combined ink-marking and perforating operation.

As usual in this class of machines in which paper is employed as the normal cutting bed, the paper is mounted in a roll 79, is conducted over the surface of the abnormal cutting bed 67 and is rerolled upon a rewind roll 80. The paper is fed a step, either at the beginning or at the end of a cycle, when the clutch mechanism 17 is thrown into operation, by the rolls 81 and 82. The roll 81 is rotated intermittently by a ratchet 83 of the roller type which is driven by the lower end of a lever 84 the upper end of which is provided with a roll 85, which engages a cam surface 86 formed on the clutch hub. The rewind roll 80 is driven by a belt 87 which passes over a pulley 88 on the rewind roll shaft and a pulley 89 constituting the hub of either the pulley 16 or the fly wheel therefor. The belt 87 is not tight so that it may constantly slip over the pulley 89, thus keeping the paper wound tight on the rewind roll notwithstanding variations in the diameter thereof.

The marking edges 54 and 55 are inked by an ink pad 90, (Figs. 3 and 7), which is mounted in a shallow pan 91. The opposite sides of the pan are provided with blocks 92 the lower edges 75

5 of which are inclined downwardly and to the right viewing Figs. 3 and 8 to engage the oppositely inclined surfaces on the upper ends of blocks 93 secured to a carriage 94. The associated pair of inclined surfaces are held in engagement in the manner illustrated in Figs. 3 and 8 by a coiled spring 95 one end of which is secured to the tray 91 and the other end of which is secured to the carriage 94.

10 The front and rear faces of the carriage 94 are each provided with a channel 96 which receives a rail 97 secured, respectively, to the front and rear faces of the work supporting bed 12. The carriage slides on the rails 97 to interpose 15 the ink pad 90 between the work mounted on the work support and the combined ink-marking and perforating die.

15 The carriage 94 is provided with an operating handle 99 by means of which the operative slides 20 the carriage to bring the ink pad 90 beneath the die and to return the carriage to the position of Fig. 3. In order to elevate the ink pad 90 vertically into engagement with the marking edges 54 and 55, the tray 91 is provided with an 25 angle plate 100 the vertical face of which engages the left-hand wall of the work supporting bed 12, viewing Fig. 3, just as the ink pad 90 is brought beneath the die thus stopping the tray and causing the blocks 93 to slide beneath the 30 blocks 92 thereby elevating the ink pad 90 into engagement with the marking edges 54 and 55. When the carriage 94 is returned to the position of Fig. 3 the springs 95 lower the ink pad by sliding the blocks 92 down the inclined surfaces 35 on the blocks 93.

35 The carriage 94 may be slid back and forth and the ink pad elevated into engagement with the marking edges 54 and 55 by a different type of operating handle 101 illustrated in Figs. 7 40 and 8.

40 The handle 101 comprises two parts, the part 102 being a rigid bar projecting forwardly from the carriage 94 and the part 103 being a lever pivoted to the part 102 and the tray 91. The 45 bar 102 and the lever 103 are maintained normally separated by a coiled spring 104 one end of which is engaged with the lever 103 and the other end of which is received in a recess 105 formed in the bar.

45 With this construction, the handle 101 may be grasped to slide the carriage 94 over the work support to position the ink pad 90 directly beneath the marking edges 54 and 55 whereupon the bar 102 and the lever 103 may be squeezed to operate the lever 103 and slide the tray 91 to the left, (Fig. 7). During this sliding movement of the tray 91, the blocks 92 ride up the inclined surfaces on the blocks 93 thus elevating the ink pad 90 into engagement with the marking 50 edges 54 and 55.

50 In operating the machine, the marking edges 54 and 55 are inked by moving the ink pad 90 in two directions normal to each other, the movement in one direction being horizontal to interpose the ink pad between the work support and the combined ink-marking and perforating die, and the movement in the other direction being vertical to bring the ink pad into engagement with the marking edges 54 and 55. After the 55 ink pad 90 has been returned to its normal position disaligned from the work support, the operative locates the work on the plate 67 against the gauge 70 if no paper is used or on the paper 70 73 against the gauge 74 when paper is used.

5 After the work has been gauged the operative steps on the treadle 32 and brings the die down toward the work the stop 35 limiting this movement when the marking edges 54 and 55 are spaced about $\frac{1}{6}$ " above the work. This small spacing insures the retention in the machine of the safety feature inherent in Model R machines while preventing blurring of the work which might occur should the marking edges 54 and 55 engage the work during the preliminary downward movement 10 of the die. The operative then steps on the treadle 18 to throw in the power mechanism for moving the die downwardly to perform the combined ink-marking and perforating operation.

10 In some cases it may be desirable to move the 15 marking edges 54 and 55 downwardly through the treadle 32 into engagement with the ink pad after it has been interposed between the die and the work support.

20 What is claimed as new, is:

1. A combined ink-marking and perforating machine having, in combination, a marking die, a work support, means for relatively operating the die and the work support to mark the work, a carriage interposable manually between the 25 marking die and the work support, and means carried by the carriage and movable vertically automatically thereon in a direction away from the work support and towards the marking die for depositing marking material thereon.

30 2. A combined ink-marking and perforating machine having, in combination, a marking die, a work support, means for relatively operating the die and the work support to mark the work, a carriage interposable manually between the marking die and the work support, a tray carried by the carriage, an ink pad carried by the tray, and means operating automatically after the carriage has been interposed between the marking die and the work support for moving the ink pad towards 35 the marking die to deposit ink thereon.

35 3. A combined ink-marking and perforating machine having, in combination, a marking die, a work support, means for relatively operating the die and the work support to mark the work, a carriage manually interposable between the 40 marking die and the work support, a tray carried by the carriage, an ink pad carried by the tray, and means operating automatically after the carriage has been interposed between the marking die and the work support for relatively moving the marking die and the ink pad to deposit ink upon the marking die comprising 45

50 operating cam surfaces on the carriage and the tray, springs for holding the tray cam surfaces from movement on the carriage cam surfaces, and a stop on the tray arranged to engage the work support and arrest the movement of the tray during the continued movement of the carriage to cause the tray cam surfaces to move on 55 the carriage cam surfaces.

55 4. A combined ink-marking and perforating machine having, in combination, a marking die, a work support, means for operating the marking die and the work support relatively to mark 60 the work, a supply of marking material, means movable manually for interposing the supply of marking material between the die and the work support, and mechanism for thereafter moving the supply of marking material in a direction 65 away from the work support and towards the die for depositing marking material thereon.
